UNITED STATES PATENT OFFICE.

THOMAS A. DE VILBISS AND GODFREY MUELLER, OF TOLEDO, OHIO, ASSIGNEES TO THE
DE VILBISS MANUFACTURING COMPANY, OF TOLEDO, OHIO, A CORPORATION OF
OHIO.

AIR-BRUSH.

1,260,522.

Specification of Letters Patent. Patented Mar. 26, 1918.

Application filed December 28, 1916. Serial No. 139,401.

To all whom it may concern:

Be it known that we, THOMAS A. DE VILBISS and GODFREY MUELLER, citizens of the United States, and residents of Toledo, in the county of Lucas and State of Ohio, have invented a certain new and useful Air-Brush; and we do hereby declare the following to be a full, clear, and exact description of the invention, such as will enable others skilled in the art to which it appertains to make and use the same, reference being had to the accompanying drawings, and to the characters of reference marked thereon, which form a part of this specification.

This invention relates to air brushes, and has for one of its objects the provision of an improved nozzle of the fan-spray type for use in connection therewith, which nozzle is simple and efficient in its construction and easily and quickly adjustable to cause the air brush to be of the fan-spray or cylindrical spray type, or to angularly adjust the fan spray with respect to the nozzle.

A further object of our invention is the provision of improved packing and guiding means for the discharge-controlling valve stem, which means, when impaired by reason of becoming worn or hardened from contact with the liquid being sprayed, is capable of being easily and quickly replaced by a new one, thereby enhancing the practicability and commercial value of apparatus of this character. This means while free to have reciprocatory movements in the barrel, is adapted to remain stationary and to permit the valve stem to have reciprocatory movements therein, thereby preventing the wear on the barrel wall incident to a movement of the packing means therein, especially if varnish, lacquer or other liquid of a similar nature is permitted to harden thereon.

Further objects and advantages of the invention will be apparent from the following detailed description thereof.

While the invention, in its broader aspect, is capable of embodiment in numerous forms, a preferred embodiment thereof is illustrated in the accompanying drawings, in which,—

Figure 1 is a side elevation of an air brush embodying the invention. Fig. 2 is a central longitudinal vertical section thereof with a portion of the handle broken

away. Figs. 3 and 4 are sections on the 55 lines 3—3 and 4—4, respectively, in Fig. 2. Fig. 5 is an end view of the air nozzle with the fan spray nozzle removed. Fig. 6 is an enlarged view of the fan spray nozzle retaining washer. Fig. 7 is an enlarged 60 section of the nut and spring washer employed in connection with the spray head, and Fig. 8 is an outer end view of the fan spray nozzle removed from the air nozzle.

Referring to the drawings, 1 designates 65 the barrel of an air brush of the character described in former United States Letters Patent No. 1,045,266, dated November 26, 1912. This barrel is carried by a handle 2 and terminates at its outer or forward end 70 in a spray head comprising the inner liquid nozzle 3 and outer air nozzle 4, both of which preferably have their outer end portions of conical form. The nozzle 2 has its inner end projected rearward into the barrel 75 bore 5 and threaded therein, as at 6, preferably in spaced relation to its forward end. The nozzle 3 in advance of its rear threaded end cooperates with the surrounding portion of the barrel wall to form an 80 annular chamber 7, which communicates at its forward end, entirely around the nozzle 3, with the annular air space 8 provided between the nozzles 3 and 4. The bore of the nozzle 3 communicates at its rear end with 85 the barrel bore 5.

A valve stem 9 is mounted for longitudinal reciprocatory movements in the barrel bore and has its forward end conically reduced to form a valve which is movable into and out of the restricted discharge orifice of the liquid nozzle 3 to open and close the same, and also to serve as a cleaning member therefor. The valve stem 9 has its rear end removably threaded, in the present instance, in a plunger member 10, which is movable in the barrel and has a reduced stem portion 11 projecting rearward therefrom through a carrying and adjusting sleeve 12 and connected by a yoke 13 to an operating finger 14, which finger has its upper end forked to straddle the barrel and is pivoted thereto, as at 15. The sleeve 12 is threaded into the rear end of the barrel and forms the outer end thrust of a coiled 100 compression spring 16 the inner end of which is in thrust contact with the plunger 10. The point of attaching of the yoke legs 105

13 to the finger 14 is below the pivot 15 so that a rearward movement of the lower end of the finger will cause a rearward movement of the plunger 10 and valve stem 9 against 5 the tension of the spring 16. The tension of this spring is determined by an inward or outward turning of the sleeve 12 with respect to the nozzle.

The air nozzle 4 is mounted on the forward end of the barrel 1, being threaded thereto, in the present instance, and the annular space 8 between it and the liquid nozzle 3 is forwardly restricted to permit the discharge of a thin annular stream of air 15 from the nozzle around the discharge end of the liquid nozzle. The annular space 7 around the rear end portion of the liquid nozzle 3 has communication with a source of air supply under pressure through a passage 17 and chamber 18, the latter having a normally closed control valve 19 therein. The stem of the valve 19 projects rearward therefrom and pivotally attaches at its rear end to the upper forked end of the operating finger 14, whereby a rearward movement of the lower end of the finger will not only impart an opening movement to the valve stem 9 but will also impart a forward opening movement to the valve 19 against 25 the tension of its closing spring.

The air nozzle 4, which preferably has its outer surface formed intermediate its ends with a conical portion, is provided in the surface of such portion with two segmental 35 grooves 20 and 21, with one disposed forward of the other and therefore of different diameters so that the ends of one groove are adapted to lap the respective ends of the other groove without communicating therewith. The spaces between the ends of the respective grooves are preferably less than a semicircle, and these spaces are disposed in substantially diametrically opposed relation with one, in the present instance, located at the top and the other at the bottom of the nozzle. The groove 20 has communication with the interior chamber 8 of the air nozzle through one or more orifices 22, as shown in Fig. 3, while the groove 21 has 50 communication with said chamber through one or more orifices 23, as shown in Fig. 4.

A supplemental nozzle 24 is mounted for rotary movements on the conical portion of the air nozzle 4 and is provided with diametrically opposed outwardly and forwardly projecting arms 25, with each arm provided with an air discharge passage 26. The inner end of one discharge passage 26 is adapted to register with the nozzle groove 60 20, while the inner end of the other passage 26 is adapted to register with the nozzle groove 21. It is thus evident that air from within the air nozzle may be simultaneously discharged from the passages 26, 26 when 65 said passages are in communication with the

respective grooves 20 and 21, and that such communication may be maintained during more than a semicircular turning of the supplemental nozzle 24 on the air nozzle. When the nozzle 24 has its position reversed from 70 that shown in Fig. 2 the inner ends of the passages 26, 26 will have been closed to the interior of the air nozzle due to the inner end of said passages registering with the closed spaces between the ends of the respective grooves.

The outer ends of the passages 26, 26 are so disposed that the streams of air discharged therefrom would intersect at a point slightly in advance of the discharge 80 ends of the nozzles 3 and 4 and in the path of discharge of fluid from said nozzles. The discharging of the opposing air streams in this manner against the paint or pigment laden fluid stream discharged from the nozzles 3, 4 causes a flattening and spreading out of said fluid in fan form, as is well understood in the art. It is evident that a turning of the supplemental nozzle 24 on the nozzle 4 within the range of the grooves 85 20 and 21 will cause the plane of the fan-spray to be angularly adjusted with respect to the axis of the spray head, thereby enabling the liquid laden stream to be broadened in a horizontal, vertical or any intermediate plane, as may be suitable to the work to be performed. Should it be desired to use the nozzles 3 and 4 alone, the supplemental nozzle 24 may be turned to place the passages 26, 26 thereof out of register 90 with the respective grooves 20, 21.

The supplemental air nozzle 24 is held seated on the conical surface of the nozzle 4 by a nut 27, which is threaded on the outer end of the nozzle 3 in position to 105 bear against the outer end of the nozzle 24, as indicated in the drawing. The nut 27 is provided on its inner face with an annular groove or channel 28, the inner wall of which is provided at its outer edge with 110 an overhanging ledge or flange 29. A spring washer 30 of suitable shape and size to fit into the channel 28 without the flange 29 is mounted in said channel and is of wavy or undulated form to provide successive 115 spaced portions which may bear against the base of the channel 28, and successive spaced portions which normally project beyond the inner side of the nut, as indicated in Fig. 7. The portions of the washer which are intended to bear against the base of the channel 28 are provided with inwardly projecting spurs 31 for engaging under the flange 29 of the nut and serving to retain the washer within the channel, and at the same 125 time permitting the nut and washer to have relative rotary movements. It is apparent that a tightening of the nut 27 with respect to the supplemental nozzle 24 will cause a compression of the spring washer 130

30 within the channel 28 so that such washer will coöperate with the nut to yieldingly hold the supplemental nozzle 24 seated in adjusted position on the nozzle 4.

70

5 The barrel 1 is provided at the rear of the liquid nozzle 3 with a transversely extending inlet passage 32 which may be connected by a hose or in any other suitable manner to the liquid to be sprayed. The 10 valve stem 9 at the rear of the liquid inlet passage 39 has a packing and guiding sleeve 33 slidingly mounted thereon and having a close sliding fit within the barrel bore and serves to prevent liquid from passing rearward thereof. The sleeve 33 preferably comprises cork or other suitable material of a fibrous nature and has its movements lengthwise of the stem limited by stop shoulders at opposite ends thereof one shoulder being designated 34 and the other comprising a nut 35, which coöperates with the adjacent end of the plunger 10 to lock the valve stem in threaded connection therewith. It is found in practice that the mounting 25 of the sleeve 33 for sliding movements on the valve stem, as well as for sliding movements in the barrel bore, permits the sleeve to remain substantially stationary in the barrel during operating movements of the 30 valve stem instead of moving with said stem, as has heretofore been the practice, and cutting or injuring the interior surface of the barrel as has frequently been the case when the packing employed has become 35 hardened by reason of the contact of varnish, lacquer or other similar liquid therewith. With our arrangement a new packing sleeve can be quickly mounted on the valve stem to replace an old one by simply withdrawing 40 the stem 9 and plunger 10 from the barrel and separating the two to permit the old sleeve to be removed and a new one placed on the inner end of the stem.

It is evident that we have provided a simple and efficient form of nozzle of the fan-spray type; that such nozzle is adjustable to angularly vary the plane in which the liquid stream is flattened and also to close the communication between the supplemental air passages 26 and the interior of the air nozzle; that we have provided simple and efficient means for yieldingly retaining the adjustable nozzle in adjusted position and have also provided a simple and efficient packing means for the valve stem whereby the wear and cutting of the barrel incident to the movement of a hardened packing member therein is avoided.

While we have herein shown and described one specific embodiment of our invention for illustrative purposes and have disclosed and discussed in detail the construction and arrangement incident to one specific application thereof, it is to be understood that the invention is not limited to the

mere detail or relative arrangement of the parts but that deviations from the illustrated form or embodiment of the invention may be made without departing from the spirit of the claims.

70

Having thus described our invention, what we claim as new, and desire to secure by Letters Patent, is,—

1. The combination with the spray-head of an air brush having a main air nozzle, 75 of a supplemental air nozzle rotatably mounted on said main nozzle and having air discharge passages leading from opposite sides of its axis for directing air streams in converging planes without the outer end 80 of said spray-head, said main nozzle having separate surface grooves in communication with the interior of the air nozzle and each in communication with one of said discharge passages during a predetermined adjusting 85 movement of the supplemental air nozzle with respect to the main nozzle and closed to said discharge passages during a different predetermined adjusting movement of the supplemental nozzle with respect to the 90 main nozzle.

2. In an air brush, a main air discharge nozzle having laterally discharging air passages in communication with the interior of said nozzle, and a supplemental nozzle 95 rotatably mounted on said main nozzle and having a plurality of spaced laterally extending discharge passages, one of said nozzles having the surface thereof which co-acts with the other nozzle provided with segmental grooves, which grooves establish communication between predetermined passages of said main and supplemental nozzle during a predetermined relative rotary adjustment of said nozzles and close such communication during a different predetermined adjustment of said nozzles.

3. The combination with the spray head of an air brush, of a supplemental air nozzle conically mounted on said spray head 110 for rotary adjustment with respect thereto and having diametrically disposed discharge passages in communication with a source of air supply through the spray head and remaining in communication with the source of air supply during a predetermined rotary adjustment through a wide arc of said air nozzle to change the angle of spray, said discharge passages being disposed to direct streams of air in converging planes which 115 meet in the line of discharge of liquid matter from said spray head.

4. The combination with the spray head of an air brush having a main air nozzle, of a supplemental air nozzle rotatably mounted on said main nozzle and having diametrically opposed air discharge passages for directing air streams in converging planes without the outer end of said spray head, 125 said main nozzle having separate surface 130

grooves in communication with the interior of the air nozzle and in communication with respective of said air passages during a pre-determined adjusting movement of the supplemental air nozzle with respect to the main nozzle.

5. In an air brush, a main air discharge nozzle having two segmental surface grooves with the ends thereof in diametrically opposed relation with respect to the nozzle axis and each having communication with the interior of said nozzle, and a supplemental nozzle rotatably mounted on said main nozzle and having diametrically opposed discharge passages for communication at their inner ends with respective of said grooves and adapted to remain in register therewith during a predetermined rotary adjustment of the air nozzle.

20 6. In an air brush, a spray head having a main discharge nozzle provided with a conical outer surface and having segmental grooves formed in the conical surface of said nozzle in longitudinally spaced relation, with the ends of one groove lapping the other and with the space between its ends diametrically opposed to the space between the ends of the other groove, a supplemental air nozzle mounted on the conical portion 25 of said main nozzle and having a pair of diametrically opposed discharge passages in communication at their inner ends with respective of said grooves and adapted to have such communication closed when the supplemental nozzle is turned to place the inner 30 ends of its discharge passages into register with the space between the ends of the respective grooves.

7. The combination with a spray head of 40 an air brush, said spray head having a main air discharge nozzle of conical form provided with segmental surface grooves in communication with the interior of said nozzle, of a supplemental nozzle mounted 45 for rotary movements on the conical portion of said main nozzle and having a plurality of discharge orifices movable into and out of communication with said grooves by a relative turning of said nozzles, and a nut 50 threaded on the outer end of said main nozzle and serving to yieldingly retain the supplemental nozzle in operative position on the main nozzle.

8. The combination with the spray head 55 of an air brush having a main air nozzle

and a supplemental air discharge nozzle mounted on said main nozzle, of a nut threaded on the outer end of said main nozzle and coacting with the supplemental nozzle to retain it seated on the main nozzle, 60 and a spring washer of undulated form carried by the nut and exerting a yielding pressure on the supplemental nozzle.

9. The combination with the spray head of an air brush and a supplemental air 65 discharge nozzle rotatably mounted on said spray head, of a nut threaded on the outer end of said spray head without the supplemental nozzle and having its inner face provided with an annular channel, and a 70 spring washer of undulated form mounted in said channel and having successive spaced portions seating against the base of the channel and successive intermediate portions in operative thrust contact with said 75 supplemental nozzle.

10. The combination with the spray head of an air brush and a supplemental air nozzle mounted thereon, of a nut threaded 80 on the outer end of said spray head without the supplemental nozzle and having its inner face provided with an annular channel, a spring washer of undulated form mounted in said channel and having successive spaced portions seating against the base of 85 the channel and successive intermediate portions in operative thrust contact with said supplemental nozzle, and means for retaining said nut and washer in relative 90 rotational engagement.

11. In an air brush, a barrel, a valve stem mounted for longitudinal reciprocatory movements in said barrel and having spaced shoulders, a guide and packing sleeve mounted on said stem for limited sliding 95 movements intermediate said shoulders and having a close sliding fit in said barrel.

12. In an air brush, a barrel, a valve stem mounted for longitudinal movements in the bore of said barrel and having stop 100 shoulders spaced longitudinally thereon, a guide and packing sleeve of fibrous material mounted on the stem intermediate said shoulders for limited sliding movements thereof and having a sliding fit in the bore 105 of said barrel.

In testimony whereof, we have hereunto signed our names to this specification.

THOMAS A. DE VILBISS.
GODFREY MUELLER.
